UNITED STATES PATENT OFFICE

EDWIN L. WIEGAND, OF PITTSBURGH, PENNSYLVANIA

ELECTRICAL HEATING UNIT

Application filed August 6, 1928. Serial No. 297,612.

This invention relates generally to electrical heating elements, and more particularly to certain improvements upon the heating elements disclosed in my Patents Nos. 1,614,330 and 1,614,331, dated January 11, 1927.

The object of the present invention is to simplify and improve the structures disclosed in those patents, and at the same time preserve and maintain all their advantageous features of operation.

For some types of work a wholly sheathed element is not absolutely necessary. This applies to applications where the unit is properly protected when mounted in certain types of appliances such as percolators, waffle irons and other devices where the exposed refractory is not too likely to become polluted.

This type of unit is used in connection with vessels made of aluminum since this metal has a high reflection factor and unless perfect contact is made the heat is best absorbed by radiation and the refractory material is naturally not damaged by the elevated temperature which would develop on the contact side of the element on aluminum vessels.

The present invention is cheaper, more easily fabricated, and in some instances is more efficient, due to the fact that fewer parts are employed and the direct radiation of heat therefore expedited.

With these objects in view, and certain others which will become apparent as the description proceeds, my invention consists in providing a one-piece sheet metal sheath in which is arranged the resistor properly embedded in a mass of refractory electrical insulating material, the edges of the sheath being turned over upon the refractory mass and holding the same in place, this refractory material being baked to the proper temperature after being smoothed off flush with the edges of the sheath.

The invention consists also in certain details of construction and combination of parts all of which will be more fully described hereinafter and pointed out in the appended claims.

In the drawing forming a part of this specification Fig. 1 is a top plan view of a heat-

ing element constructed in accordance with my present invention; Fig. 2 is a bottom plan view of the same; Fig. 3 is a transverse sectional view and Figs. 4, 5 and 6 are views showing different shapes of heating elements all embodying the details of my present invention.

In all forms of the present invention a sinuous resistor 1 is enveloped within a mass of suitable electrical insulating heat conducting material 2. The resistor preferably consists of a flat ribbon wire of suitable metal, shown as bent back and forth across the element in comparatively close bends, with its edges presented to the broad faces of the element. It will be understood, however, that a resistor wire of the usual form can be employed instead of the ribbon form. The mass 2 may be of any suitable refractory insulating material, and I have found magnesium or aluminum oxide or zirconium silicate, either individually where possible, or a compound of them together when desirable, with a suitable binding material such as clay, to give the necessary plasticity during fabrication and to effect homogeneity in the final product.

The mass 2 of refractory material which surrounds and envelopes the resistor is highly compacted within a sheet metal sheath or casing 3, this sheet metal sheath or casing being constructed of very thin sheet metal and comprising a bottom portion 3^a and side portions 3^b, the side portions being comparatively shallow or narrow as compared with the width of the bottom portion. This sheath or casing can therefore be described as a one-piece sheet metal sheath, channel shaped in cross section.

The resistor, it will be noted, is arranged within the sheet metal sheath but is spaced therefrom, and the refractory material 2 which envelopes the resistor completely fills the sheath and therefore properly spaces the resistor within the sheath.

The refractory material is highly compacted within the sheath and the edges 3^c of the sides 3^b of the sheath are rolled or turned over the adjacent portions of the refractory material, that is to say the edges of the sides of the sheath are rolled or turned toward each

other thereby overlapping the edges of the refractory and serving to maintain the refractory material within the sheath.

The ends of the resistor 1 are connected to 5 terminals 10 which have their enlarged inner ends or bases to which the resistor is attached embedded within the mass 2 of refractory material. The terminals extend outwardly through holes 11 produced in the bottom of 10 the sheath, the holes being of sufficient size to insure proper spacing and consequential insulation and, as illustrated, the hole is closed by a washer 12 of mica or other suitable insulating material that fits over the 15 terminal and is engaged against the outer side of the bottom of the sheath.

In addition to compacting the refractory material and turning over the edges of the sheath, this material is dried and baked either 20 by an external source of heat or by energizing the resistor. As a result of this baking, the refractory is converted into a homogeneous hard filling, and due to the fact that the outer surface thereof is made flush with the 25 rolled over edges of the sheath, these rolled over edges serve to securely maintain the refractory firmly within the sheath. In other words, the sheath, refractory, and resistor enveloped therein, are rigidly and intimately 30 united into a composite product.

In Figs. 1, 2 and 3 I have shown the heating element substantially in the form of a ring, while in Fig. 4 it is shown in the form of a circular heating element having a small 35 central circular opening. In Fig. 5 I have shown it as triangular in form, and in Fig. 6 I have shown it as V-shaped. In my patents previously referred to, such shapes were also employed, and furthermore the heating element disclosed in said patents were in some 40 instances, curved or dished to conform to certain shapes of articles to be heated, and in my present invention the heating element can also be so bent or shaped if desired, this bending or shaping process of course taking place 45 prior to the drying and baking of the refractory material.

In order to more securely bind the refractory and sheath together, a suitable coating 50 of glazing may be arranged upon the refractory and baked at the same time that the refractory is baked.

My present type of heating element possesses certain advantages over any heating elements heretofore constructed, inasmuch as I only employ the sheath, resistor and filling of refractory material, thus dispensing with a separate covering plate or strip. This not only avoids the use of this amount of metal, but it brings about a more rapid radiation of heat as this covering member heretofore employed necessarily absorbed a definite quantity of heat units.

Furthermore, a perfectly smooth heating unit can be provided inasmuch as the refrac-

tory is made flush with the rolled over edges, and a perfectly smooth uniform surface is provided.

It will also be understood that the sheath can have its bottom portion either perforate or imperforate and still accomplish all of the proper functions of the sheath or casing. Furthermore, by dispensing with the separate cover, a more uniform product can be obtained by rolling the edges of the sheath over the adjacent portions of the refractory and these rolled-over edges impart to the sheath a definite amount of rigidity, particularly when the ring or circular type of heating element is produced.

It will thus be seen that I provide a simplified electrical heating element consisting of fewer parts and one which is superior to those heretofore produced insofar as the rapid and direct radiation of heat is concerned.

Having thus described my invention, what I claim is:

1. An electrical heating unit of the character described comprising a one piece sheet metal sheath substantially channel shaped in cross section, a resistor arranged within said sheath, a homogeneous compact mass of refractory insulating material completely enveloping the resistor and filling the said sheath except for the space occupied by said resistor, the opposite edges of said sheath being bent over toward each other and overlapping the adjacent edges of the refractory material and embedded therein so that the refractory material is flush with the turned-over edges of the sheath, and terminals connected with said resistor and emerging from said sheath and adapted for connection with a source of current.

2. In an electrical heating unit of the character described, comprising a one-piece sheet metal sheath substantially channel shaped in cross section and having its entire peripheral edge bent upwardly to form an open face casing, a resistor arranged within said casing, a homogeneous compacted mass of refractory insulating material filling said casing except for the space occupied by said resistor, said resistor being supported solely by said refractory insulating material, the opposite edges of said casing being bent over toward each other and overlapping the adjacent edges of the refractory material and embedded therein so that the refractory material is flush with said overturned edges, and terminals connected with said resistor and emerging from said sheath and adapted for connection with a source of current.

3. In an electrical heating unit of the character described, comprising an endless sheet metal sheath substantially channel shaped in cross section and having its entire peripheral edge bent upwardly to form an open face casing, a resistor arranged within said casing, a homogeneous compacted mass of refractory

insulating material filling said casing except for the space occupied by said resistor, said resistor being supported solely by said refractory insulating material, the opposite edges of said casing being bent over toward each other and overlapping the adjacent edges of the refractory material and embedded therein so that the refractory material is flush with said overturned edges, and terminals connected with said resistor and emerging from said sheath and adapted for connection with a source of current.

4. An electrical resistance heating unit of the character described having an exposed refractory face and comprising a sheath substantially channel-shaped in cross-section, a resistor arranged within said sheath, a homogeneous compacted mass of refractory insulating material enveloping said resistor, the opposite edges of said sheath being bent over toward each other and overlapping the adjacent edges of the refractory material and disposed substantially flush with the exposed face of the unit and terminals emerging from said sheath and adapted for connection with a source of current.

5. An electrical resistance heating unit of the character described having an exposed refractory face and comprising a sheath substantially channel-shaped in cross section, a resistor arranged within said sheath, a mass of refractory insulating material enveloping said resistor, the opposite sides of said sheath having inwardly directed portions, the refractory insulating material interlocking with said inwardly directed portions and having its surface disposed substantially flush with the edges of said sheath.

6. In an electrical resistance heating unit of the character described having an exposed molded refractory face and comprising a sheath, a resistor arranged within said sheath, a mass of refractory insulating material enveloping said resistor, the opposite sides of said sheath having inwardly directed portions, the refractory insulating material interlocking with said inwardly directed portions and having its surface disposed substantially flush with the edges of said sheath.

50 In testimony whereof I hereunto affix my signature.

EDWIN L. WIEGAND.
